SKI ATTACHING DEVICE

Carl O. Johnson, Kenmore, N. Y.

Application March 8, 1939, Serial No. 260,567

12 Claims. (Cl. 280—11.35)

My invention relates in general to skis, and in particular to a device whereby a shoe may be readily attached to or detached from a ski.

The principal object of my invention has been to provide a device having two interengageable members, one of which may be attached to the shoe and the other of which may be attached to the ski, and means for detachably locking the members together.

Another object has been to provide a device of this nature which can be so adjusted that the wearer of the ski may, in an emergency, detach the shoe from the ski by a quick, rearward movement thereof.

Another object has been to provide attaching means so designed that the portion which is attached to the shoe will in no wise hamper the normal use thereof when the ski is detached from the shoe.

Another object has been to provide the portion of the device which is attached to the shoe with serrations or tooth formations, whereby slippage in walking or in hill climbing is prevented.

A further object has been to provide a device so designed and constructed that all working parts are enclosed, the surfaces which are exposed to the snow being so designed that they may be readily freed from accumulated snow before being engaged.

Moreover, my device is of such a nature that it may be easily attached to the shoe or to the ski without alteration of either.

Furthermore, my device is of such nature that the ski will be kept in perfect alignment with the shoe of the wearer, but will in no wise impede the free, normal use of the foot of the wearer.

The above objects and advantages have been accomplished by the device shown in the accompanying drawings, of which:

Fig. 1 is a fragmentary, longitudinal, sectional view taken on line 1—1 of Fig. 2.

Fig. 2 is a sectional, plan view taken on line 2—2 of Fig. 1.

Fig. 3 is a transverse, sectional elevation taken on line 3—3 of Fig. 5.

Fig. 4 is a transverse, sectional elevation taken on line 4—4 of Fig. 1.

Fig. 5 is a bottom, plan view of that portion of my device which is carried by the shoe.

Fig. 6 is a fragmentary, transverse, sectional view showing the lock pin in its emergency position, taken on line 6—6 of Fig. 1.

Fig. 7 is a side elevation of a modified form of my device, partly in section, and taken on line 55

7—7 of Fig. 8, showing the portions in positions ready for assembling.

Fig. 8 is a plan view of that portion of the device which is secured to the ski, partly in section, taken on line 8—8 of Fig. 7.

Fig. 9 is a transverse, sectional view taken on line 9—9 of Fig. 7.

Fig. 10 is a transverse, sectional view of my device taken on line 10—10 of Fig. 8, showing the parts in assembled positions.

Fig. 11 is a transverse, fragmentary, sectional view taken similar to Fig. 10 and also on line 10—10 of Fig. 8, showing the lock pin in its emergency position.

15 Referring now to the form of invention shown in Figs. 1—6, inclusive, the preferred form of my device comprises a base plate 15 which is preferably secured to the ski 16 by means of nails 17 and screws 18. The plate is provided near its central portion with a housing 20 which is raised somewhat above the general level of the base, as shown in the drawings. The wedge-shaped member 21 of my device is formed at the rear portion of this casing. This wedge-shaped member, as shown in Figs. 3 and 6, has its side walls 22 tapered inwardly in the vertical plane and tapered rearwardly in a horizontal plane. The tapers of the inclined surfaces of the side walls are so proportioned that the wedge member will be firmly engaged with the coacting socket member 23, but at the same time may be quite easily detached therefrom.

35 The socket member 23 of my device, which is secured to the sole 24 of the shoe by means of rivets or other suitable fastening means 25, is provided with an upstanding flange 26 for engagement with the forward edge of the sole of the shoe. This flange not only provides a suitable stop for the shoe but also strengthens the socket member transversely and prevents its being spread or bent when in use. The socket member is provided with a centrally arranged body part 30 and with two wing members 31, one arranged on each side of the body part and projecting downwardly therefrom. The lower exposed surfaces of the wing members may be notched and thus provided with teeth or transverse serrations 32 which aid materially in climbing a hill, since the toothed portions will give added traction to the wearer. The inner adjacent surfaces 33 of the wings are tapered inwardly toward the center in a vertical plane and are tapered inwardly in a horizontal plane toward the back of the shoe, these tapered sur-

faces corresponding to the tapered surfaces formed on the wedge member 21 of the device.

When the socket member 23 is attached to the shoe and is placed in registerable position with the wedge member 21, a longitudinal movement forwardly of the shoe in relation to the ski will cause the tapered surfaces of these two parts to be brought into engagement. In order to hold the parts in engagement, I provide a lock pin 36. This lock pin is slidably carried in a suitable aperture 35 formed in the wedge member 21 of my device, and it is designed to project laterally therefrom for engagement with a suitable abutment formed on the socket member when in fully engaged position. For convenience, the teeth 32 may be so formed that the lock pin will engage behind one of them, as shown in fragmentary manner in Figs. 2 and 5. The lock pin is formed on its outer end 36 with a cam-shaped surface which may be of semi-spherical form and the pin is designed to be held in partially engaged relation with the abutment of the socket member by means to be hereinafter described.

The opening 35 is formed in a sleeve member 40 which bridges the space between the side walls 22 of the wedge member 21. Oppositely-arranged slots 41 are formed in this sleeve member and a slot 42 is likewise formed in the inner end of the lock pin opposite the slots 41.

Mounted within the recessed portion of the casing 20 is an actuating lever 43. This lever is pivotally mounted intermediate its ends upon a pivot pin 44 which is carried by the casing, and preferably extends downwardly thereon. The rearward end of this actuating lever is provided with a relatively narrow arm 45 which extends into and through the slots 41 in the sleeve 40 and engages with the slot 42 in the lock pin 36, whereby the lock pin will be reciprocated back and forth within the aperture 35 by the actuation of the lever 43. The forward end of the actuating lever extends forwardly and lies within an enlarged housing portion 46. This housing portion, as clearly shown in Figs. 1 and 4, has its upper surface arranged at a slight angle and in the inclined wall thus formed a sleeve 50 is mounted which carries a control lever 51. The control lever is provided with a centrally arranged spherical member 52 through which a pivot pin 53 passes. This pivot pin is carried by the sleeve 50. The control lever has a downwardly extending actuating arm 54 and an upwardly extending control arm 55. This control arm is provided at its upper end with a spherical portion, as shown, immediately under which is formed a detent recess 56, to be hereinafter described. The actuating arm 54 of this control lever extends downwardly and engages with an aperture 60 formed in the forward end of the actuating lever 43. So as to compensate for the inclination of the wall which supports the control lever 51, the forward end of the actuating lever is preferably twisted somewhat so as to be arranged at an angle with the body part of the lever, as clearly shown in Fig. 4.

As clearly shown by Figs. 2, 3 and 5, when the socket member 23 is in fully engaged position with the wedge member 21, the lock pin 36 will engage the socket member behind one of the teeth 32 and thus hold the socket member in place against detachment from the wedge member until the parts are disengaged by the operation of the control lever 51. Occasion arises, however, where the user of the skis de-

sires to be able to detach his shoe from the ski in an emergency. In such cases, the lock pin 36 is withdrawn within the aperture to the position shown in Fig. 6 where only the cam-shaped end 36 will be projecting, in which position the pin will act in the nature of a bullet fastener. When in this position, a quick jerk of the socket member backwardly in relation to the wedge member will cause the lock pin to be pushed inwardly because of the engagement only of the cam-shaped end of the pin, thereby clearing the abutment and allowing the socket member to be withdrawn completely from engagement with the wedge member. In order to hold the lock pin in this partly extended position, a detent clip 61 is pivotally attached to a bracket 62 carried on the housing portion 46. This detent clip is of such length that when it is passed over the control arm 55 of the control lever and is engaged with the detent recess 56 thereof, the actuating lever 43 will be held in such position that the pin will be only partly extended, as above described.

A helical spring 63 is provided for holding the actuating lever 43 in its fully operative position, as shown in Fig. 2. One of its ends is suitably attached to the inside of the housing 20 and its opposite end is attached to the actuating lever, as shown in Fig. 2.

While the socket member of my invention is shown in the form just described as being attached to the shoe, and the wedge member as being attached to the ski, it is obvious that the parts may be reversed, and such a modified form of structure is shown in Figs. 7-11, inclusive, of the drawings, to which attention is now called.

In this form of invention, the socket member 70 is preferably carried by means of a plate 71 and it is secured to the ski 72 by means of screws 73 and nails 74. This socket member is provided with two oppositely-arranged wing portions 75 between which is formed a dovetail groove 76. As shown in Fig. 8, this groove is tapered longitudinally from the rear of the ski toward the forward end thereof; and, as shown in Figs. 10 and 11, the side walls 80 bounding the groove 76 are tapered in a vertical plane or inclined downwardly.

The wedge member 81 in this form of the invention is carried by and attached to the sole 82 of the shoe of the wearer, and it is preferably provided at its forward end with a flange 83 against which the forward edge of the sole is adapted to bear and which gives added strength to this member of my device. The wedge member 81 is provided with a plate member 84 by which the member may be secured to the bottom of the sole of the shoe. A tongue member 85 is centrally carried by the plate member 84 and has its side walls tapered longitudinally and vertically a degree substantially equal to the degree of the taper of the groove 76 of the socket member. Instead of being formed on its under surface with teeth, as in the other form of device, the bottom surface of this tongue member 85 is preferably smooth and formed with a groove 86, thus providing an abutment 87 for engagement with the lock pin 90.

The lock pin 90 of this form of my device is mounted within an aperture 91 formed in one of the wing portions 75 and is pressed outwardly by means of a helical spring 92, mounted within the aperture 91. The forward end 93 of this lock pin is cam-shaped, as in the other form of invention,

whereby emergency engagement of the wedge member with the socket member may be brought about. Extending forwardly from and forming a part of one of the wing members 75 is the housing 94 which is preferably made integral with the plate 71. Mounted within this housing is the actuating lever 95 of this form of my invention. This actuating lever is pivotally mounted upon a pivot pin 96, extending downwardly from the upper wall of the housing. The rear end of this actuating lever is formed with an arm 100 which engages with a slot 101 formed in the lock pin 90, whereby when the actuating lever is operated, the pin will be reciprocated in its aperture. The forward end of the actuating lever is located beneath an enlarged housing portion 102 and is provided with an aperture 103. The enlarged housing portion 102 carries the control lever 104 of this form of device, which is disposed within a sleeve 105, suitably secured to the housing portion, said lever being mounted upon a pivot pin 107 carried by said sleeve. This control lever has a downwardly extending actuating arm 106 which engages with the aperture 103 of the actuating lever and whereby such lever is oscillated. The control lever is provided with an upwardly extending control arm 110 in which is formed a detent notch 111. A detent clip 112, pivotally carried by the housing enlargement, is engageable with the notch 111 of the control lever when the same is moved to the dot-and-dash line position of Fig. 9, in which position the lock pin 90 will be held in its partially retracted position, as shown in Fig. 11, which is the emergency position of the pin.

From the foregoing description it will be evident that since the socket member in the form of invention of Fig. 1 and the wedge member in the form of invention of Fig. 2 is secured to the forward part of the sole under the toe of the shoe, the wearer will have perfectly free ankle and foot movement without the usual restraint which comes about when the shoe is strapped rigidly to the ski. Another advantage of securing the shoe member of my device at the forward end of the toe portion of the sole is that when the shoe is detached from the ski, the shoe member will not in any way hamper the normal use of the shoe but, on the other hand, the teeth, notches, or serrations on the bottom surface of such member will provide additional traction and help in walking on ice or snow. Moreover, my invention is so designed that all the working parts are enclosed and effectively protected against being rendered inoperative by an accumulation of snow or ice. Furthermore, the exposed engaging surfaces of my invention are such that they may be readily cleared of any accumulation of snow by means of the finger or any ready instrument. When it is desired to engage the shoe with the ski, it is only necessary to force the shoe member into engagement with the ski member. The tapered or dove-tail-shaped interengaging portions of the members will be readily engaged without the necessity of accurate registration and when assembled the lock pin in each form of the invention will be automatically forced inwardly, allowing the members to become engaged, after which it will spring outwardly in locking position, thereby keeping the two members in such locked position. When it is desired to have the members so interlocked that they may be disengaged in an emergency, it is only necessary to bring the detent clip of either form of invention in engagement with the control

75 arm of the control lever, which will hold the lock pin in partially retracted position, in which position the cam-shaped end thereof only will be engaged with the shoe member, as hereinbefore described, thus making it possible for the wearer to quickly disengage the shoe from the ski while in the act of skiing and without having to manually operate any part of the control mechanism. Such detachment of the shoe from the ski may

10 be accomplished by a quick backward movement of the shoe. When the lock pin is in its fully engaged position and it is desired to detach the shoe from the ski, it is only necessary for the wearer to reach down and move the control lever against the tension of the spring in either of the forms of invention, which will cause the actuating lever to retract the lock pin, allowing the member carried by the shoe to be readily disengaged from the member carried by the ski by rearward longitudinal movement.

15 While I have shown the socket member of the form of Fig. 1 and the wedge member of the form of Fig. 2 as formed on their under surfaces with the series of teeth 32 or serrations, it is 20 obvious that these surfaces may, if desired, be smooth. Furthermore, while I have shown the engaging surfaces of the wedge and socket member as being tapered or dovetailed longitudinally, it is obvious that the side walls may be substantially parallel and one or the other of the members provided with a stop to limit the amount of relative movement. In such a modified form, each of the opposite sides of the lock pin would engage an abutment to prevent relative movement 25 of the member in either direction.

30 Furthermore, if desired the actuating lever may be omitted and the control lever engaged directly with the lock pin, the slot in the lock pin being elongated to allow inward movement of the pin when in its emergency position.

35 These and other modifications of the details herein shown and described may be made without departing from the spirit of my invention or the scope of the appended claims, and I do 40 not, therefore, wish to be limited to the exact embodiment herein shown and described, the form shown being merely a preferred embodiment thereof.

Having thus described my invention, what I 45 claim is:

1. A ski attaching device, comprising a ski member, a shoe member, said members being slidably longitudinally to interengage each other, one of said members being of closed housing formation, and locking means enclosed within said housing and projectable laterally therefrom to engage said other member.

2. A ski attaching device, comprising interengaging members carried by the ski and a shoe, said members being slidable longitudinally to interengage each other, one of said members being of closed housing formation, locking means enclosed within said housing and projectable laterally therefrom to engage said other member, and actuating means substantially enclosed within and carried by said housing formation for releasing said locking means to disengage said members.

3. A ski attaching device, comprising a ski member, an interengaging shoe member, a lock pin movably carried by the ski member and locking engageable with the shoe member, said lock pin having two operative positions and one inoperative position, and means for holding said pin in said operative positions.

4. A ski attaching device, comprising a ski member, an interengaging shoe member, a lock pin movably carried by the ski member and lockingly engageable with the shoe member, said lock pin having a fully extended position, a partially extended position, and a withdrawn position, means for yieldably holding said lock pin in said fully operative position, means for moving said pin to said withdrawn position, and detent means for holding said pin in said partially extended position.

5. A ski attaching device, comprising interengaging members carried by the ski and a shoe, a closed housing formed on the members carried by the ski, a lock pin carried by the housing and laterally movable for engagement with a locking abutment formed on the member carried by the shoe, a control lever carried by said housing, and an actuating lever pivotally enclosed within said housing, said actuating lever having one of its ends engageable with said lock pin and its other end engageable with said control lever.

6. A ski attaching device, comprising interengaging members carried by the ski and a shoe, a closed housing formed on the members carried by the ski, a lock pin carried by the housing and laterally movable for engagement with a locking abutment formed on the member carried by the shoe, a control lever carried by said housing, an actuating lever pivotally enclosed within said housing, said actuating lever having one of its ends engageable with said lock pin and its other end engageable with said control lever, and detent means carried by said ski member and engageable with said control lever for holding said lock pin in partially unlocked position, whereby the shoe may be easily detached from the ski in an emergency.

7. A ski attaching device, comprising interengaging members carried by the ski and a shoe, a closed housing formed on the members carried by the ski, a lock pin carried by the housing and laterally movable for engagement with a locking abutment formed on the member carried by the shoe, said lock pin having a cam-shaped outer end, actuating means engageable with the lock pin and substantially enclosed within the housing, and detent means carried by said housing for holding said lock pin with its cam-shaped end only engageable with the shoe member, whereby the shoe may be easily detached from the ski in an emergency.

8. A ski attaching device, comprising a socket member carried by the shoe, a wedge member carried by the ski, each of said members having

tapered dovetailed surfaces and being engageable by relative longitudinal movement, said wedge member constituting a closed housing, and locking means enclosed within said housing for retaining said members in locked position.

5 9. A ski attaching device, comprising a socket member carried by the shoe, a wedge member carried by the ski, each of said members having tapered interengaging surfaces, a lock pin slidably mounted within said wedge member and engageable with an abutment carried by said socket member, a housing formed on said wedge member, an actuating lever pivotally enclosed within said housing, a control lever, and means connecting said actuating lever with said lock pin and said control lever.

10 10. A ski attaching device, comprising a socket member carried by the shoe, a wedge member carried by the ski, each of said members having tapered interengaging surfaces, a lock pin slidably mounted within said wedge member and engageable with an abutment carried by said socket member for positively locking the interengaged parts, a housing formed on said wedge member, 15 an actuating lever pivotally enclosed within said housing, a control lever, means connecting said actuating lever with said lock pin and said control lever, and detent means carried by said housing and engageable with said control lever for holding said lock pin in partially unlocked position, whereby the shoe may be easily detached from the ski in an emergency.

11 11. The combination with a ski and a shoe of fastening means, comprising a one-piece ski member, a one-piece shoe member, said members having dovetailed interengagement, said ski member being of closed housing formation, locking means enclosed within said housing member and projectable therefrom to engage said shoe member and said shoe member being located at and secured to only the toe part of the shoe.

12 12. A ski attaching device, comprising interengaging members carried by the ski and a shoe, said members having dovetailed surfaces for interlocking engagement, a closed housing formed on the members carried by the ski, a lock pin carried by the housing and laterally movable for engagement with a locking abutment formed on the member carried by the shoe, a control lever carried by said housing, and an actuating lever pivotally enclosed within said housing, said actuating lever having one of its ends engageable with said lock pin and its other end engageable with said control lever.

CARL O. JOHNSON.
